UNITED STATES PATENT OFFICE.

ALBERT B. CLISSON, OF SYRACUSE, NEW YORK, ASSIGNOR, BY MESNE ASSIGNMENTS, TO THE PROSPERITY COMPANY, INC., OF SYRACUSE, NEW YORK, A CORPORATION OF NEW YORK.

OPERATING MECHANISM FOR PRESSING MACHINES.

Application filed September 4, 1924. Serial No. 735,840.

This invention relates to pressing machines, as garment and laundry pressing machines, and particularly to machines in which the movable pressing element or head is moved preliminary toward closed position, and in so doing shifts the motion transmitting parts into motion transmitting relation, and has for its object connections operable by the movement of such motion transmitting parts or by the movable head to connect the power motor to such connections, when said connections have reached effective motion transmitting relation.

The invention consists in the novel features and in the combinations and constructions hereinafter set forth and claimed.

In describing this invention reference is had to the accompanying drawings in which like characters designate corresponding parts in all the views.

Figure 1 is a side elevation of a pressing machine embodying this invention.

Figure 2 is a fragmentary front elevation thereof.

Figure 3 is a fragmentary detail view of the handle for the operating or controlling mechanism.

This pressing machine comprises, generally, coacting pressing elements one of which is movable toward and from the other, actuating mechanism for the movable element, including an intermittently movable power member, motion transmitting means between the power member and the movable element, including parts normally arranged out of effective transmitting relation and movable into such relation by a preliminary movement of the head or movable element toward closed position, power means as an electric or other motor, and operating mechanism operable to connect the power means to said member, and means operated by the motion transmitting connections for effecting the automatic operation of the operating mechanism, when the motion transmitting parts have been brought into effective motion transmitting relation.

I have here shown my invention as applied to a conventional type of garment and laundry pressing machine, including a stationary pressing element or buck 1, and a movable element or head 2, movable toward and from the buck 1. The buck 1 is mounted upon a suitable bracket 3, which in turn is

mounted upon a table 4, suitably carried by legs or pedestals 5, 5^a. The head is carried on the forward arm of a vertically movable lever or yoke 6, pivoted between its ends at 7, to a standard 8, rising from the frame of the machine or the rear leg 5 thereof, the rear arm of the lever carrying a suitable weight 9 for counter-balancing the head, for moving it toward open position. Also a spring 10 is usually connected to the rear arm of the lever 6 to act in conjunction with the weight 9.

The intermittently actuated power member is here shown as a lever 11, pivoted at 12 between its ends to the lower end of the leg 5^a, this lever being actuated by an intermittently rotatable shaft 13 having an eccentric 14 thereon, coacting with a face 15 on the front end of the lever 11. The shaft 13 makes a half revolution during each operation and is actuated by the power means, which is usually an electric motor 16. This motor is preferably constantly running, instead of an alternately starting and stopping, and the motion is transmitted to the shaft 11 through mechanism housed within the casing 17, and including a periodic or half revolution clutch of any suitable construction. As the construction thus far described, forms no part of this invention, further description is thought to be unnecessary, it being merely necessary to bear in mind that the periodic clutch is thrown to its "in" position manually or by a manual operation, and automatically thrown to its "out" position after the shaft 13 has completed each half revolution.

The lever 11 is caused to follow the cam by a suitable spring 18.

The motion transmitting means between the lever 11 and the head 2, in addition to the yoke or lever 6, comprises toggle links 19 and 20, pivoted together at 21, and pivoted respectively at 22 and 12 to the rear arm of the yoke or lever 6, and to the frame, the link 20 being usually pivoted to the frame on the same pivot 12 that the lever 11 is mounted on. In addition to this toggle which when straightened applies pressure to the head 2, the motion transmitting means includes a connection for straightening the toggle and causing it to apply the pressure. This connection is here shown as a thrust link 23 pivoted at 24 to the rear arm of the lever 11, and normally arranged in nearly upright posi-

tion, it being held in such position by a nut 25 threading on a screw 26, which nut is pivoted at 27 to the rear leg 5^a. A spring 28 is inserted between the frame and the link 23 and 5 tends to thrust the link against the nut 25. This thrust link 23 coacts with an extension 29 of the link 19, the thrust link 23 and the extension 29 being provided with coacting teeth 30 and 31.

10 When the press is open and the toggle links 19, 20 are folded rearwardly, the tooth 31 is located to the rear of the tooth 30 of the thrust link 23, but when the head 2 is moved preliminarily toward closed position by pulling 15 down the handle 32, the toggle links 19, 20 are moved to such a position that the teeth 31 and 30 come into engagement, and hence, any downward movement of the power lever 11 is transferred through the thrust link 23 20 to the toggle and causes the toggle to move more nearly into a straightened position and applies pressure to the press head. The parts are preferably adjusted, so that, the teeth 31 and 30 do not come into engagement 25 until after the press head 2 has been preliminarily closed or until the press head 2 is so close to the work on the buck 1, that it is impossible for the operator to have his hands or fingers between the buck 1 and the head 2, 30 or if he does have his hands in this position, the head cannot be closed far enough to bring the tooth 31 into engagement with the tooth 30.

The operation mechanism for throwing the 35 clutch to connect the motor 16 to the shaft 13 comprises a rock shaft 32^a extending forwardly and rearwardly of the machine on the right hand side thereof and having a rock arm 34 thereon and also a handle 35 at its 40 front end. The rock arm 34 coacts with the rock arm 36 mounted on a rock shaft 37 in the clutch housing 17. The rock shaft 37 serves to throw the clutch to its "in" position. As here shown the rock arm 34 is 45 shifted to actuate the arm 36 and is provided with a pawl 38 pivoted at 39 and coacting with the tooth 40 on the arm 36. The arrangement of the pawl 38 and tooth 40 is such that depression of the handle 35 rocks the 50 shaft 32^a and arm 34 in a counter clockwise direction, causing the pawl 38 during such movement of the arm 34, to press against the tooth 40 and rock the lever 36 in a clockwise direction, until the pawl clears the tooth 40. 55 When the operator releases his hold on the handle the weight of the arm 34 returns the handle to its normal position and the pawl 38 ratchets to the front left hand side of the tooth 40. Suitable set screws 41 and 42 are 60 provided for adjusting the relative positions of the pawl 38 and tooth 40. The construction of this operating mechanism forms no part of this invention.

65 The connection between the motion transmitting means operated by the lever 11 and

the operating mechanism of the shaft 32^a and associated parts, by which said operating mechanism is automatically actuated when the head has been preliminarily closed, and the toggle brought into effective motion transmitting relation to the thrust link 23, comprises an arm movable by the preliminary movement of the head 2, a latch associated with the operating mechanism, a member operated by the arm and coacting with the latch 70 and arranged to engage the latch during the preliminary closing movement of the head 2, and actuate the latch to cause it to actuate the shaft 32^a, and hence, thrust the clutch 75 "in".

43 designates the arm, which is here shown as fixed to the toggle link 20 to move therewith, this arm extending forwardly and together with the link 20 forming a bell crank.

44 designates the latch depending from a rock arm 45 extending inwardly to the left from the rock shaft 32^a, the latch being pivoted at 46 to said rock arm 45. The latch is formed near its lower end with a tooth 47 and also with an inclined face 48 below the 90 tooth, this inclined face 48 coacting with a fixed part at 49. During the downward movement of the latch, such coaction causes the latch to be moved on its pivot against the action of a spring 50 to the right, and causes 95 the latch to disengage itself from a member 51 which coacts therewith. This member 51 is here shown as a lever pivoted at 52 and connected by a link 53 to the front end of the arm 43 it being connected to the arm 43 by a 100 lost motion connection, as a pin and slot connection 54. The engaging projecting end 55 of this lever 51 also coacts with inclined face 48.

In operation, as the press head is being 105 preliminarily closed by pulling down on the handle 32, the links 19 and 20 are being moved toward the position shown in Figure 1 and the arm 43 is moved downwardly. The movement of the arm 43 exerts a downward pull on the link 53 actuating the lever 51 on its pivot, causing the lever 51 to pull downwardly on the latch 44, as the engaging or projecting end 55 of the lever 51 is engaged with the tooth 47 of the latch. The 115 downward movement of this latch 44 rocks the shaft 32^a of the clutch operating mechanism and causes the clutch to be thrown to its "in" position, so that the shaft 13 makes a half revolution from the position diametrically opposite that shown in Figure 1, and depresses the lever 11. As the thrust link 23 and the extension 29 of the toggle 19 are in motion transmitting relation the actuation of the power lever 11 is transferred to the head 2. The downward movement of the power lever 11 actuates the thrust link 23 and causes the toggle links 19 and 20 to move more nearly into their dead center line, or into the position shown in Fig. 1. After the arm 43 125 130

is moved downwardly during the movement of the toggle link 20, the cam face of the latch engages the part 49 and the latch 44 is thrust laterally or to the right Fig. 2, against the action of the spring 50, and is thus released from the lever 51, so that, the handle 35 and shaft 32^a are free to return to their normal position for manual operation to open the press. When the latch 44 moves upwardly to its normal position the latch face 48 is brought into engagement with the end 55 of the lever 51, as shown in Fig. 2.

During the manual operation of the shaft 32^a to open the press the latch 44 is depressed and hence moves relatively to the member 51, and during its downward movement the tooth 47 ratchets into engagement with the member 51, the member 51 with its engaging or projecting end 55 having, during the opening movement of the press, been raised into position to engage the shoulder 47 of the latch 44 by the lever 43, so that the spring acting on the latch 44 moves the latch into engagement with the tooth 55 of the lever 51 and the parts are in position for the next operation.

What I claim is:—

1. In a pressing machine, the combination of coacting pressing elements, one movable toward and from the other, actuating mechanism for the movable element including an intermittently movable power member, motion transmitting connections between the power member and the movable element including parts normally out of effective motion transmitting relation and movable into such relation by a preliminary movement of the movable element toward closed position, power means and operating mechanism operable to connect the power means to said member, said operating mechanism including a shiftable clutch section and means operated by said motion transmitting connections to effect the automatic throwing of the clutch section into clutching position when said parts have been brought into effective motion transmitting relation by the preliminary closing of the movable element.

2. In a pressing machine, the combination of coacting pressing elements, one movable toward and from the other, actuating mechanism for the movable element including an intermittently movable power member, motion transmitting connections between the power member and the movable element including parts normally arranged out of effective motion transmitting relation and movable into such relation by the preliminary movement of the movable element toward closed position, power means, operating mechanism operable to connect the power means to said member including a periodic clutch including a shiftable clutch section and means operated by the motion transmitting connections for shifting said section into clutching position and said operating mech-

anism also having a handle for shifting the clutch section into operative position when the press is closed.

3. In a pressing machine, the combination of coacting pressing elements, one movable toward and from the other, actuating mechanism for the movable element including an intermittently movable power member, motion transmitting means between the power member and the movable element, including parts normally arranged out of effective motion transmitting relation and movable into such relation by a preliminary movement of the movable element toward closed position, power means, and operating mechanism operable to connect the power means to said member, and means operated by the motion transmitting connections for effecting the automatic operation of the operating mechanism when said parts have been brought into effective motion transmitting relation, the last mentioned means comprising a latch member connected to the operating mechanism, a member connected to one of said parts and arranged to normally engage the latch member, and means for forcing the latch member out of engagement with the member coacting therewith, when the press reaches closed position, and thereby permitting the operating mechanism to return to its normal position.

4. In a pressing machine, the combination of coacting pressing elements, one movable toward and from the other, actuating mechanism for the movable element including an intermittently movable power member, motion transmitting means between the power member and the movable element, including parts normally arranged out of effective motion transmitting relation and movable into such relation by a preliminary movement of the movable element toward closed position, power means, and operating mechanism operable to connect the power means to said member, and means operated by the motion transmitting connections for effecting the automatic operation of the operating mechanism when said parts have been brought into effective motion transmitting relation, the last mentioned means comprising a latch member connected to the operating mechanism, a member connected to one of the said parts and arranged to normally engage the latch member, the latch member being formed with an inclined face, a throw off part arranged in the path of said face and forcing the latch member out of engagement with the member coacting therewith as the press reaches its closed position, such member which coacts with the latch being also arranged to engage the inclined face, in order to ratchet into engagement with the latch member as the press is opening.

5. In a pressing machine the combination of coacting pressing elements, one movable

- toward and from the other, actuating mechanism for the movable element including an intermittently movable power member, motion transmitting means between the power member and the movable element including parts normally arranged out of effective motion transmitting relation and movable into motion transmitting relation by the preliminary movement of the movable element toward closed position, power means, operating mechanism operable to connect the power means to said member and having an operator-operated part by which said mechanism is operated to connect the power means and said member to open the press from closed position, a movable latch associated with the operating means, an arm movable with one of the motion transmitting parts, and connections between the arm and the latch including a piece having a tooth coacting with the latch to engage and actuate the latch and parts connected thereto during the preliminary closing of the press. 6. In a pressing machine the combination of coacting pressing elements, one movable toward and from the other, actuating mechanism for the movable element including an intermittently movable power member, motion transmitting means between the power member and the movable element including parts normally arranged out of effective motion transmitting relation and movable into motion transmitting relation by the preliminary movement of the movable element toward closed position, power means, operating mechanism operable to connect the power means to said member and having a handle operable for actuating said means to connect the power means and said member to open the press from closed position, a movable latch member associated with the operating mechanism, an arm movable with one of said motion transmitting parts, a lever coacting with the latch to actuate it and a link connecting said arm and the lever whereby the motion of the motion transmitting part is transferred through said arm, link and lever to the latch to actuate the operating mechanism during the preliminary closing of the press. 7. In a pressing machine the combination of coacting pressing elements, one movable toward and from the other, actuating mechanism for the movable element including an intermittently movable power member, motion transmitting means between the power member and the movable element including parts normally arranged out of effective motion transmitting relation and movable into motion transmitting relation by the preliminary movement of the movable element toward closed position, power means, operating mechanism operable to connect the power means to said member and having a handle to actuate said operating mechanism to connect the power means, and said member to effect the opening of the press from closed position, a movable latch member movable with said handle, an arm movable with one of the motion transmitting parts, a lever coacting with the latch to actuate it during the preliminary closing of the press and a link connecting said arm and the arm and link being connected to said arm by a lost motion. 8. In a pressing machine the combination of coacting pressing elements, one movable toward and from the other, actuating mechanism for the movable element including an intermittently movable power member, motion transmitting means between the power member and the movable element including parts normally arranged out of effective motion transmitting relation and movable into motion transmitting relation by the preliminary movement of the movable element toward closed position, power means, operating mechanism operable to connect the power means to said member and having a handle operable for actuating said means to connect the power means and said member to open the press from closed position, a movable latch member associated with the operating mechanism, an arm movable with one of said motion transmitting parts, a lever having a projection coacting with the latch and a link connecting said arm and the lever, the lever engaging the latch to actuate the operating mechanism during the preliminary closing of the press, and means to shift the latch out of engagement with said projection when the latch has been operated by the projection.

In testimony whereof, I have hereunto signed my name, at Syracuse, in the county of Onondaga, and in the State of New York, this 20th day of August, 1924.

ALBERT B. CLISSON.
